US00D809137S

(12) **United States Design Patent** (10) **Patent No.:** **US D809,137 S**
(45) **Date of Patent:** **** Jan. 30, 2018**

(54) **COMPONENT OF INJECTION DEVICE**

(71) Applicant: **SANOFI-AVENTIS DEUTSCHLAND GMBH**, Frankfurt am Main (DE)

(72) Inventor: **Jochen Ratjen**, Nacka (SE)

(73) Assignee: **SANOFI-AVENTIS DEUTSCHLAND GMBH**, Frankfurt am Main (DE)

(**) Term: **15 Years**

(21) Appl. No.: **29/583,214**

(22) Filed: **Nov. 3, 2016**

Related U.S. Application Data

(62) Division of application No. 29/494,077, filed on Jun. 17, 2014, now Pat. No. Des. 788,909.

(57) **CLAIM**

The ornamental design for a component of injection device, as shown and described.

DESCRIPTION

FIG. 1 is a perspective view of a component of injection device, showing my new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The broken lines in the figures consisting of evenly-sized dashes depict portions of the component of injection device that form no part of the claim.

1 Claim, 4 Drawing Sheets
